Inventor

A. J. Koepsell

By Watson E. Coleman
Attorney

UNITED STATES PATENT OFFICE.

AUGUST J. KOEPSSELL, OF MAYVILLE, WISCONSIN.

BOOKCASE.

1,421,012.

Specification of Letters Patent. Patented June 27, 1922.

Application filed July 17, 1920. Serial No. 396,960.

To all whom it may concern:

Be it known that I, AUGUST J. KOEPSSELL, a citizen of the United States, residing at Mayville, in the county of Dodge and State 5 of Wisconsin, have invented certain new and useful Improvements in Bookcases, of which the following is a specification, reference being had to the accompanying drawings.

This invention relates to book cases and 10 more particularly to a rotary book case provided with adjustable shelves.

An important object of the invention is to provide in a book case of this type, means whereby certain of the shelves thereof may 15 be readily adjusted.

A further object of the invention is to provide a novel construction in a book case of this type whereby the books carried thereby are so positioned that their titles may be 20 read from a point lying beyond the periphery of the book case.

A further object of the invention is to provide a device of this character which is extremely simple and efficient in operation 25 and which presents a pleasing appearance to the eye.

Further objects and advantages of the invention will become apparent throughout the course of the following description:

30 In the accompanying drawings, wherein for the purpose of illustration is shown a preferred embodiment of my invention and wherein like reference characters designate like parts throughout:

35 Figure 1 is a vertical sectional view taken through a book-case embodying my invention.

Figure 2 is a transverse sectional view therethrough; and

40 Figure 3 is a detailed view illustrating the operating mechanism by means of which the adjustable shelves are shifted.

In the construction of my invention I preferably employ a base or standard 10 in 45 which is rotatably mounted the lower end of a vertical shaft 11, some suitable antifriction device 12 being disposed intermediate a shoulder formed on the shaft and the base 10.

To the lower end of the shaft immediately 50 above the base 10 a shelf 13 is secured to the shaft as at 14 in any desired manner and held against rotation with relation thereto. At the upper end of the shaft a shelf 15, similar in shape, is secured to the shaft as 55 at 16, and held against rotation with relation thereto. Mounted intermediate the

shelves 13 and 15 is a plurality of shelves 17, similar in shaping to the shelves 13 and 15 and provided with central openings through which the shaft 11 extends. 60

Each of these shelves is in the form of a cross having the arms 20 thereof of equal length, and each shelf is provided adjacent the ends of the arms thereof with apertures 18. Vertical rods 19 extend through these 65 apertures and are secured to the shelves 13 and 15 in any desired manner to prevent vertical movement thereof. Two of the brace rods 19 are provided at each arm of the shelf and are disposed at opposite sides 70 thereof.

Mounted upon each of the arms of the shelf inwardly from the brace wires 19 thereof is a vertical support triangular in cross section and having one of the sides thereof 75 disposed toward the end of the arm. As will be seen by inspecting the drawings, the other two sides of the triangular structure forming an angularly disposed support against which books may be disposed, these 80 sides being preferably disposed at an angle of 45 degrees to the longitudinal axis of the arms 20.

If desired, upstanding partition walls 21^a 85 may be provided centrally of the upper face of each of the arms 20 extending inwardly to abut a housing 22 which is preferably rectangular in cross section and has its faces disposed at an angle of 45 degrees to the axes 90 of the arms 20. It will be seen that books placed upon the shelf will be alined by the walls of the housing 22 and the triangular support 21, so that they are at an angle of approximately 45 degrees to the sides of the arm and accordingly face outwardly toward 95 the peripheral circle formed by the arms when rotating, thereby permitting ready reading of the titles thereof. If the partition wall 21^a is used, this further assists in the alining of the volumes upon the shelves. 100

The vertical shaft 11 is preferably rectangular in cross section and is provided upon oppositely disposed faces thereof with gear teeth 23. Rotatably mounted within the housing 22 of each of the adjustable 105 shelves 17 is a pair of shafts 24 arranged upon opposite sides of the shaft 11 and provided with gears 25 having the teeth thereof meshing with the gear teeth 23 of the shaft 11. These shafts likewise have secured thereto gears 26 meshing with one another and one of the shafts has rotatably 110

mounted thereabout a gravity operated dog 27, which dog engages a ratchet 28 carried by the other of the shafts 24. Rotatably mounted in suitable supports extending 5 downwardly from the under surface of each of the shelves 17 is a shaft 29 provided upon its inner end with a gear 30 meshing with one of the gears 26. The outer end of the shaft 29 is provided with an operating 10 handle 31 suitably squared for the reception of the crank 32.

In the use of my device when it is desired to adjust the shelves 17 to the size of the books being used in the case, the crank 32 15 is applied to the shaft 29 of the shelf which it is desired to adjust, and the shaft rotated. This rotation is transmitted by the gear 30 to the shafts 24 through the gears 26 causing the shafts to rotate in opposite directions as indicated by the arrows. This rotation causes the shelf 17 to be elevated. If it is desired to lower the shelf the fingers 20 may be inserted through the open top of the housing 22 and the dog 27 lifted from engagement with the ratchet 28 permitting a 25 reverse rotation of the shafts 24 and consequently lowering the corresponding shelf. If desired, the dog 27 may be provided with an upstanding portion 33 which may be engaged by the fingers of the hand to elevate the dog.

It will be understood that many changes are possible in the shape, size and general arrangement of the parts herein shown, and 35 I accordingly do not limit myself to the specific construction hereinbefore set forth, but may make any such changes, without departing from the spirit of the invention or the scope of the subjoined claims.

40 Having now described my invention, what I claim is:

1. A rotary book case including a rotatable support, a plurality of shelves carried by said support, each of said shelves embodying a plurality of radial arms, a vertical support extending upwardly from each of said arms to the next adjacent arm and adjacent the outer ends thereof, said vertical supports being triangular in cross section 45 and each having one of the sides thereof disposed toward the outer end of its respective arm and at right angles to the axis of the arm, the remaining sides being disposed at an angle to the longitudinal axis of said 50 arm, a polygonal housing disposed centrally of the shelf and surrounding said support, the sides of said housing corresponding in number to the number of arms with which the shelf is provided, the corners of the housing being coincident with the axes of said arms and the sides of the housing being disposed toward the space intermediate the 55 arms.

2. A rotary book case comprising a rotatable support, a plurality of shelves car-

ried by said support, each of said shelves embodying a central portion and a plurality of radial arms intersecting the central portion, the arms of the several shelves being in alignment, a vertical support extending 70 upward from each of said arms adjacent the outer end thereof, said supports being triangular in cross section and having one of the sides thereof disposed toward the outer end of its respective arm and at right angles 75 to the axis of the arm and in spaced relation to the end of the arm, said outwardly facing side being less in width than the width of the arm, the remaining sides of the triangular support being disposed at an angle to the longitudinal axis of the arm, a polygonal housing disposed centrally of the shelf around said support, the housing having corners equal in number to the number of the arms and said corners being coincident with the axes of the arms, the side faces of said housing being spaced at all points from the edges of the arms.

3. In a rotary book case a rotatable support, a plurality of shelves carried by said support, each of said shelves embodying a plurality of radial arms, a vertical support extending upwardly from each of said arms adjacent the outer ends thereof, said supports being triangular in cross section and 90 each having one of the sides thereof disposed toward the outer end of its respective arm, a polygonal housing disposed centrally of the shelf and surrounding said support, the sides of said housing corresponding in number to the number of arms with which the shelf is provided, said sides being disposed toward the space intermediate the arms, the remaining sides of said triangular support 95 being disposed at an angle to the axial center of said arms and a partition wall extending centrally of each of said arms and connecting said support and said housing.

4. In a rotary book case a rotatable support, a plurality of shelves carried by said support, each of said shelves being substantially cross shaped and having the arms thereof of equal length, a vertical support extending upwardly from each of said arms adjacent the outer ends thereof, said supports being triangular in cross section and 110 each having one of the sides thereof disposed toward the outer end of its respective arm and parallel thereto, the remaining sides of said supports being disposed at an angle 115 to 45 degrees to their respective arm, and a vertical housing disposed centrally of each of said shelves, said housing being substantially rectangular in cross section and having the sides thereof disposed toward the space 120 intermediate the arms.

5. In a rotary book case a rotatable support, a plurality of shelves carried by said support, each of said shelves being substantially cross shaped and having the arms 130

thereof of equal length, a vertical support extending upwardly from each of said arms adjacent the outer ends thereof, said supports being triangular in cross section and each having one of the sides thereof disposed toward the outer end of its respective arm and parallel thereto, the remaining sides of said supports being disposed at an angle of 45 degrees to their respective arms, a vertical housing disposed centrally of each of said shelves, said housing being substantially rectangular in cross section and having the sides thereof disposed toward the space intermediate the arms, and a partition wall connecting the inwardly directed apex of each of said supports with said housing at the junction of two of the sides thereof.

6. In a rotary book case, a rotatable vertical support horizontal shelves carried by said support, and means for vertically adjusting said shelves embodying, a rack formed upon said support, a shaft rotatably supported by each of said shelves and meshing with said rack, a second shaft rotatably supported by each of said shelves upon the under surfaces thereof and provided upon

its inner end with a pinion and a second gear secured to said first named shaft and meshing with said pinion.

7. In a rotary book case a rotatable vertical support, horizontal shelves carried by said support and means for vertically adjusting said shelves, embodying racks formed upon opposite faces of said support, a pair of shafts rotatably supported by each of said shelves upon opposite sides of said support, gears secured to said shafts and meshing with said racks, other gears secured to each of said shafts and meshing with the corresponding gear of the other shaft of the pair, an operating shaft rotatably supported by each of said shelves upon the under face thereof, a pinion carried by said operating shaft upon the inner end thereof and engaging one of said last named gears and a gravity operated dog rotatably mounted upon one shaft of each pair to coact with a ratchet carried by the other shaft of each pair.

In testimony whereof I hereunto affix my signature.

AUGUST J. KOESELL.
